FLUID ACTUATED SWITCH

Jesse Oliver Steele, Lund, Utah

Application March 30, 1940, Serial No. 327,005

5 Claims. (Cl. 200—83)

The present invention relates to a switch mechanism adapted for use primarily in controlling the operation of an electrically driven pump and has for its primary object to provide a fluid connection with the pump and arranged for actuating a diaphragm connected with a switch operating mechanism whereby to control the opening of the switch by any variation in the vacuum or pressure generated by the pump such as a drop in the line voltage connected with the pump, or a failure of the phase controlling the pump motor, or a reversal of such phase, or in case the driving connection between the pump motor and the pump should become broken.

A still further object is to provide a fluid operated switch of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a front elevational view of the switch operating mechanism with parts broken away and shown in section.

Figure 2 is a vertical sectional view taken substantially on a line 2—2 of Figure 1.

Figure 3 is an end elevational view of the shaft operating member, and

Figure 4 is a fragmentary detail of a modified arrangement of the spring employed for operating the shaft operating member in one direction.

Referring now to the drawings in detail wherein for the purpose of illustration I have disclosed a preferred embodiment of the invention, the numeral 5 designates a casing having an opening 6 in its top wall and within which is secured a rubber diaphragm 7 by means of a dome-shaped plate 8 which is bolted as at 9 to the edge portions of the diaphragm to secure the same to the casing. The plate 8 forms a chamber 10 immediately above the diaphragm and to the plate is attached a pipe 11 leading to a suitable source of suction such as the intake end of a pump impeller (not shown).

A rod 12 is secured at its upper end to the diaphragm 7, the lower end of the rod being pivoted to a shaft operating member designated generally at 13 which is in the form of a block having a vertically extending slotted opening 14 formed

therein. Arms 15 and 16 project outwardly from one side of the block, the arm 15 being positioned at the upper edge of the block and the arm 16 being positioned at the lower edge thereof, and 5 threaded in said arm are set screws 17 and 18 respectively.

A shaft 19 is journalled in bearings 20 formed on the inside of the casing 5, one end of the shaft being positioned in the slotted opening 14 10 and is formed with a pair of lugs 21 and 22 projecting laterally from opposite sides of the shaft. The set screw 17 constitutes an adjustable operating connection for the lug 21 and shaft 19, and the set screw 18 constitutes a similar operating 15 connection for the lug 22, as more clearly shown in Figure 3 of the drawings, the shaft being rotated in one direction by either an upward or downward movement of the rod 12. A coil spring 23 is provided for yieldably maintaining 20 the lugs in engagement with the respective set screws.

A hook-shaped catch 24 projects laterally from one side of the shaft 19 and is engageable with the downwardly projecting edge 25 of a cup-shaped plate 26 formed at the lower end of a pair of pivoted arms 27 which are pivoted as at 28 to brackets 29 secured to the wall of the casing 5. A pair of expansible coil springs 30 are positioned against the rear wall of the casing 5 30 for yieldably urging the plate 26 outwardly. Hook-shaped stops 27' project forwardly from the rear wall of the casing for engagement with the arms 27 to limit the outward movement thereof.

35 A plurality of knife switches for controlling an electric motor of a type generally employed for operating a pump are shown generally at 31, 32 and 33.

The switch is of the three pole type, the knife 40 blades being pivoted respectively at 34, 35 and 36 on the insulation block 37 secured to the rear wall of the casing and the three ends of the knife blades are respectively engageable with the contacts 38, 39 and 40, also mounted on the insulation block 41 secured to the rear wall of the casing.

The lower ends of the knife blades are connected by an insulation cross member 42 from 45 which the handle 43 projects downwardly 50 through the bottom portion of the casing.

A guide block 44 is also secured to the rear wall of the casing having an opening 45 formed therein through which the rod 12 is slidably inserted, the under side of the block being engaged 55 by an expansible coil spring 46 which abuts at its

lower end a washer 47 secured in threaded adjusted position on the rod by means of a nut 48 to regulate the tension of the spring.

It will be noted that the shaft 19 is adapted for movement only in one direction, that is, for latch releasing movement, the stops 17 and 18 preventing movement of the shaft in an opposite direction. The spring 46 is arranged in a position to exert pressure on the rod 12 and in a direction opposed to the suction created in the chamber 10. Accordingly, a decrease in the suction in the chamber 12 will permit the spring 46 to move the rod 12 downwardly whereby to cause the set screws 17 and 18 to rotate the shaft 19 in a direction for releasing the latch 24, whereupon the springs 30 will move the switch into open position. Likewise, a failure in the operation of the pump for any cause, to which the suction pipe 11 is connected, will cause a similar opening actuation of the switch.

Also, should an increase in the suction in the chamber 10 develop the upward movement of the rod 12 will cause the lower set screw 18 to move its associated lug 22 upwardly and to rotate the shaft 19 in a similar latch releasing movement and to also open the switch.

In the modified form of the invention illustrated in Figure 4, the spring designated at 49 is positioned above the guide block 44 and is secured in compressed condition by the nut 50 threaded on the rod 12. In this form of the invention the spring will serve to act against pressure created in the chamber 10 rather than by suction, as heretofore explained.

It is believed the details of construction, operation and advantages of the device will be readily understood from the foregoing without further detailed explanation.

Having thus described the invention, what I claim is:

1. A switch comprising a spring actuated switch member, a movable member having a catch releasably engaging the switch member, a diaphragm responsive to pressure or suction variations and means operatively connecting the movable member with the diaphragm for releas-

ing the catch when said last named means is moved in either of two directions.

2. A switch comprising a spring actuated switch member, a rotatable shaft, a catch carried by the shaft and releasably engaging said switch member, a radially extending projection on the shaft, a diaphragm responsive to pressure or suction variations and means operated by the diaphragm and engaging the projection for rotating the shaft in a direction for releasing the catch.

3. A switch comprising a spring actuated switch member, a rotatable shaft, a catch carried by the shaft and releasably engaging said switch member, a radially extending projection on the shaft, a diaphragm responsive to pressure or suction variations, a rod connected to the diaphragm and adjustable means carried by the rod and engaging the projection for rotating the shaft in a direction for releasing the catch.

4. A switch comprising a spring actuated switch member, a rotatable shaft, a catch carried by the shaft and releasably engaging said switch member, a pair of radially extending projections at diametrically opposite sides of the shaft, a diaphragm responsive to pressure or suction variations, a rod connected to the diaphragm and a pair of adjustable members carried by the rod, one of said adjustable members engaging the top of one projection and the other adjustable member engaging the bottom of the other projection and adapted upon a movement of the rod in either direction to rotate the shaft in a direction for releasing the catch.

5. A switch comprising a spring actuated switch arm, a rotatable member having a catch releasably engaging the arm, a diaphragm responsive to pressure or suction variations, a reciprocable member connected to the diaphragm and means operatively connecting the reciprocable member to the rotatable member for actuating the latter to release the catch upon a predetermined movement of the reciprocable member in either direction.

JESSE OLIVER STEELE.
